UNITED STATES PATENT OFFICE

CHESTER C. DE PEW, OF KEYPORT, NEW JERSEY, ASSIGNOR TO WHIRLPOOL INCORPORATED, A CORPORATION OF NEW YORK

WHIRLPOOL GAME DEVICE

Application filed July 18, 1931. Serial No. 551,642.

This invention relates generally to new and useful improvements in games and more specifically to a novel game requiring a high degree of skill in the manipulation of a spherical element around a helical path or guiding means forming a whirlpool and which is provided with openings or pockets of different numerical value disposed adjacent the several convolutions of the helical path.

10 The invention as herein disclosed and claimed constitutes an improvement over the one shown in the Patent No. 1,798,900 of March 31, 1931.

An object of the invention is to provide a 15 game similar to the one described in the above mentioned patent but in which the helical guiding means is so formed as to actually provide a whirlpool effect when the game is played.

20 Various objects and advantages of the invention will be in part obvious from an inspection of the accompanying drawing and a careful consideration of the following particular description and claims of one form 25 of mechanism embodying my invention.

In the drawing:

Figure 1 is a top plan view of the invention.

Figure 2 is a longitudinal section taken 30 approximately at the center of the device.

Figure 3 is a cross section with portions broken away.

With reference to the drawing, 10 designates a substantially horizontal table board 35 in which is formed a circular opening 11. In circular alignment with this opening there is secured in any suitable manner, a bowl 12 having sloping side walls 13 and a bottom 14 sloping towards the center. The aforesaid bowl is of frustro-conical formation disposed in an inverted position.

Supported within this bowl there is a helicoid 15 preferably formed of circular tubing and arranged so as to be equally spaced from 40 the side walls 13 to a degree not in excess of the diameter of the ball 16 so that it may provide a path or track in conjunction with the side walls for the ball to roll upon in a downward direction towards the bottom 45 of the bowl. This helicoid termi-

nates at its upper end in a substantially straight portion 17 which extends along above the table top in spaced relation and provides a side rail which in conjunction with a similar rail 18 spaced parallel therefrom forms a guiding means for the ball 16 when projected from its starting point at 19 by any suitable means such as a cue (not shown). This relatively straight path should be of such length as to enable the ball to acquire considerable momentum before it enters the helical guide and the rails 17 and 18 should be spaced from the top of the table a little more than one half the diameter of the ball.

In the side walls 13 there are formed a 55 number of openings 20 of more or less elliptical formation disposed so that when the ball is rolling upon the upper side of the helical guide 15 as shown at 21 it will readily enter any one of the openings. However, the openings should be so spaced away from the lower side of each convolution of the helicoid that the ball may have a clear and uninterrupted path when travelling at high speed in contact with the under-side of the helicoid since it 60 will be maintained in that position as long as its rolling speed is sufficiently high to develop centrifugal force enough to maintain it in that position. A further opening 25 is formed in the bottom 14 preferably at the 65 center and a stop 26 may be provided so as to restrain the ball from unnecessary circular motion when it has reached the bottom of the bowl. The openings may be connected to conduits 30 so that the ball may be conducted to a tray 31 at the player's end of the table.

The operation of the device is as follows: 70 The ball is initially placed at the beginning of the straight path and struck forcibly with a cue or set into motion by any other means either manually or mechanically operated at the will of the player. As the ball contacts with the helix, it will be drawn downwardly into the bowl, and due to the centrifugal force generated by its diversion from the straight path will travel in contact with the lower side of the convolutions and the sloping side walls of the bowl which will tend to support the ball; this position of the ball will 75 be maintained as long as the ball retains con- 80

siderable centrifugal force. Sooner or later, however, depending upon the speed of the ball, it will lose its momentum and to a correspondingly greater degree its centrifugal force which will result in the ball dropping from its position under the coil as shown in Fig. 2, to the dotted line position on top of the coil from where it will readily roll into an adjacent opening. The openings may be 10 suitably numbered as shown in Fig. 3 so that a score may be kept of the play as it proceeds.

Variations may be resorted to within the scope of the invention and portions of the improvements may be used without the others 15 whilst not departing from the spirit of the invention.

Having thus described my invention, I claim:

20 1. A whirlpool game device, comprising a conically formed helicoid having a vertical axis, and side walls conformed to the angle of said helicoid and arranged in spaced relation therewith; said side walls provided with openings disposed adjacent the convolutions 25 of said helicoid.

30 2. A whirlpool game device, comprising a frustro-conically formed bowl having side walls, a helicoid within said bowl spaced from said walls, and a substantially horizontal relatively straight guide connected to said helicoid at its upper convolution; said side walls being provided with openings disposed adjacent the convolutions of said helicoid.

35 3. A whirlpool game device, comprising a helical guiding means for a rolling element, side walls conformed to said guiding means, and a track formed of said helical means and said side walls to support the rolling element; said walls being provided with openings adjacent the helical means.

40 4. In apparatus of the class described, in combination, a substantially horizontal table, a conically formed bowl having side walls converging downwardly about a vertical axis, a tapered helicoid conforming to said side walls disposed within said bowl in spaced relation therewith, and a relatively straight guiding means disposed upon said table and connected to said helicoid.

45 5. In apparatus of the class described, the combination with a rollable element, of a relatively straight guiding means for said element, a conically formed helicoid having a vertical axis and connecting with said straight guiding means, and walls in spaced relation with said helicoid to form a track therewith for said rollable element.

60 6. In apparatus of the class described, the combination with a rollable element, of a relatively straight guiding means for said element, a conically formed helicoid having a vertical axis and connecting with said straight guiding means, walls having openings and arranged in spaced relation to said helicoid to form a track therewith for said

rollable element, a bottom wall under said helicoid having at least one opening, and conduits connected to all of said openings and extending away from said helicoid.

Signed at Keyport, in the county of Monmouth and State of New Jersey this 16th day of July, 1931.
